UNITED STATES PATENT OFFICE

EDWARD DANNER, OF NEWARK, OHIO, ASSIGNOR TO THE LIBBEY GLASS MANUFACTURING COMPANY, OF TOLEDO, OHIO, A CORPORATION OF OHIO

GRINDING MACHINE

Application filed September 28, 1923. Serial No. 665,268.

My invention relates to a machine for grinding glass, and more particularly for grinding parallel faces on a plurality of glass articles simultaneously.

The more specific features of this invention will appear as the description proceeds.

Referring to the accompanying drawings forming a part of this specification:

Fig. 1 is a side elevation of a machine embodying my invention, parts being broken away;

Fig. 2 is a plan view of the machine, likewise having parts broken away;

Figs. 3, 4, 5 and 6 are views of various forms 10 of article holders which may be used in the machine;

Fig. 7 is a section on the line 7—7 of Fig. 5;

Fig. 8 is a section on the line 8—8 of Fig. 6.

Any suitable frame, 10, supports the various portions of the machine.

The grinding wheel, 11, is supported upon a suitable bearing, 12, and is driven through any suitable connection to a source of power, belt pulleys 13 and 14 being shown to receive 25 the power.

A central upright shaft, 15, drives the grinding wheel, and near the top of this same shaft there is fixed a worm, 16, which drives worm wheels 17 and 18 on shafts 19 and 20. 30 Each end of shafts 19 and 20 carries a spiral gear 21, meshing with a spiral gear, 22, actuating an article carrier. The operating mechanism of each carrier is the same, so that but one need be described.

35 A sleeve, 23, is fixed to and projects downward from the hub of gear 22, and carries an article holder at its lower end. As shown, there is a hub piece, 24, fitting into the lower end of the sleeve and held against relative rotation by a screw, 25, which projects through the sleeve into a longitudinal groove, 26, in the hub piece. A lock nut, 27, limits the entrance of the hub piece into the sleeve. The lower end of the hub piece carries a lug, 28, adapted to fit into a keyway 29, in an article holder.

40 As shown in Figs. 3 to 6 inclusive, the article holders are of a substantially circular outline, with a slot, 30, in one side leading to a central opening. This slot will receive

the reduced upper portion of the hub piece and when properly positioned the holder may be slid down into place on the end of the hub piece with the lug 28 in one of the key ways, 29.

55 The holder, 31, shown in Fig. 3, comprises a circumferential member, 32, with transverse peripheral notches, 33, each adapted to receive a glass article, 34. Lugs 35, 36, project from the periphery on the sides of the slot 30, and each has a series of corrugations, 37, to hold rings, 38, in adjusted position thereon. The ring on lug 36 is attached directly to one end of a belt, B. The belt is passed around the articles on the holder and attached to the ring on lug 35 by means of a spring, 39, which produces constant tension that will hold the articles in place.

60 The holder 40, shown in Fig. 4, has similar peripheral notches, 41, for the reception of articles. A series of radially slidable rods, 42, are constantly urged inward by springs, 43. Each rod carries, at its outer end, a contact piece, 44, which is adapted to hold two articles in place in adjacent notches.

65 The holder, 45, shown in Fig. 5 has a circular series of perforations, 46, which are adapted to receive articles, 47, larger at one end than at the other. The smaller ends are held in place by a series of contact members, 48, attached to radially slidable rods, 49, urged inward by springs, 50, while the larger ends are held in place by similar contact pieces, 51, attached to radially slidable rods, 52, urged inward by springs, 53.

70 The holder, 54, shown in Fig. 6 is adapted to hold oblong articles, and has a series of slots, 55, for their reception. The edges of the slots are cut away, as at 56, for ease in grasping the articles when removing them from the holder.

75 Through the hub of gear 22 is passed a sliding rod, 60. The sliding rod 60 has a swivel connection, 61, at its upper end, with a chain, 62, which passes over guide pulleys, 63 and 64, to a pull rod, 65. The pull rod slides through a bracket, 66, on the frame, and its lower end is connected to a chain, 67, which passes around an elevating sprocket 67', shown on Fig. 2, operated from handle 80

68, through miter gears, 69, 70. A counter-balancing weight, 71, is attached to the lower end of chain 69. Collars 72, 73, limit the travel of the pull rod, 65.

6 The slide rod, 60, projects downward into the sleeve 23 and carries, near its lower end, a member, 74, extending out through a slot, 75, in the sleeve, and attached to a hood, 76, which slides vertically outside of the sleeve.

10 The hood has a bearing surface, 77, on its under side, which is adapted to bear upon the upper side of the articles being ground. Removable weights, 78, make it possible to adjust the pressure exerted by the hood.

15 The operation of the device is as follows: Article carriers suitable for the particular articles to be ground are selected and filled with articles. Handles 68 are operated to raise the hoods, 76, and the carriers are slid into place on the hub pieces. The hoods are lowered and the surfaces, 77, rest on the upper ends of the articles. The handles, 68, are turned until the chains 67 beneath the rods 65 are slack, and a catch, not shown, holds 20 the elevating rollers in that position. As the shaft 15 rotates, the grinding wheel is whirled beneath the articles resting thereon, and the holders are turned so that the grinding of the various articles will be uniform and the 25 grinding surface rubs past each article from all directions, as the article is turned with respect to the direction of travel of the wheel.

30 After the articles in a holder are ground on one side, the hood is lifted, the holder removed from the hub piece, turned over, and replaced. Then the hood is lowered, and the other face of the article is ground. The stop 35 73 may be set so that the articles will be relieved of the weight of the hood when they 40 are sufficiently ground, with the result that the distance between ground faces is the same in all the articles, not only in those that are ground in one holder, but those that are ground in holders adjusted to the desired distance.

45 Where means for keeping the articles from dropping out of the holder are omitted, as in the holder shown in Fig. 6, the loading is done with the holder in place in the machine, 50 and after the first grinding the hood is raised and the articles taken out and turned over one at a time, the hood lowered, and the second surface ground. The function of the holder during grinding is essentially that of 55 a guide, the hood being depended upon to press the articles against the grinding surface. Articles of considerable size may be handled individually between grindings without serious loss of time, but where a considerable number are ground in one holder it is an advantage to fasten them in so that they may be turned with the holder and individual handling between grindings may be avoided.

In some cases the use of the hood might be

omitted and the articles might be clamped in a holder that would exert sufficient pressure to produce the desired grinding. The approach of the holder to the grinding surface is limited by a flange, 79, on the hub piece, and when the articles are clamped tightly enough to prevent their movement relative to the holder during grinding, the amount they are ground may be limited by the position of the flange.

70 Other changes may be made within the scope of the appended claims without departing from the spirit of the invention.

What I claim is:

1. In grinding apparatus, a member having a flat grinding surface, a holder adapted to revolve a plurality of articles about an axis normal to the grinding surface, a presser member moving with the holder and having a flat surface adapted to contact an annular series of articles in the holder, and means to maintain the presser member with its pressing surface parallel with the grinding surface.

2. A grinding machine comprising a grinding wheel having a vertical axis and a horizontal grinding face, a plurality of article carriers each comprising a vertical rotating slotted sleeve, a hub piece carried by the lower end of the sleeve and having an enlargement on its lower end, an article holder adapted to receive and hold a series of articles around its axis and to be mounted upon the hub piece enlargement to rotate therewith, a hood slidably mounted outside of the sleeve and having a lower face parallel with the grinding face and adapted to rest upon articles in the holder, a rod slidably mounted within the sleeve and connected with the hood through the slot of the sleeve, a device for raising and lowering the rod, and a stop to limit the descent of the rod.

95 In testimony whereof I have hereunto signed my name to this specification.

EDWARD DANNER.
